(57) **CLAIM**

The ornamental design for an eco friendly dispenser as shown and described.

DESCRIPTION

FIG. 1 is a perspective view of an eco-friendly dispenser, showing my design;

FIG. 2 is a side elevation view of the eco-friendly dispenser of FIG. 1;

FIG. 3 is a side elevation of the eco-friendly dispenser of FIG. 1, being the opposite side of the view shown in FIG. 2; FIG. 4 is a front elevation view of the eco-friendly dispenser of FIG. 1;

FIG. 5 is a rear elevation view of the eco-friendly dispenser of FIG. 1;

FIG. 6 is a top view of the eco-friendly dispenser of FIG. 1; FIG. 7 is a bottom view of the eco-friendly dispenser of FIG. 1; and,

FIG. 8 is a top, rear, right perspective exploded view of the eco-friendly dispenser of FIG. 1.

Some features, including all text, are depicted in dotted lines to show environment and form no part of the claimed design.

1 Claim, 5 Drawing Sheets
